CLAIM

U.S. PATENT DOCUMENTS

The ornamental design for a height finder for a surveying instrument support, as shown and described.

DESCRIPTION

D. 255,104 5/1980 Haidek D10/74
D. 266,746 11/1982 Wilson D10/74
3,021,599 2/1962 Odom ..... 33/138 X
3,390,461 7/1968 Anderson ..... 33/138 X

FIG. 1 is a front and top-left perspective view of a height finder for a surveying instrument support showing my new design;

FIG. 2 is a front and top-right perspective view thereof; FIG. 3 is a left side-rear perspective view thereof; and FIG. 4 is a rear and bottom perspective view thereof. The broken line showings of FIGS. 1-4 are environmental only and form no part of the claimed design.

FIG. I

FIG.2

FIG. 3

FIG. 4
